UNITED STATES PATENT OFFICE.

WILLIAM C. MEYER, OF BUFFALO, NEW YORK, ASSIGNOR TO BUFFALO WEAVING AND BELTING COMPANY, OF BUFFALO, NEW YORK, A CORPORATION OF NEW YORK.

ANTISQUEAK STRIP.

Application filed March 20, 1928. Serial No. 263,157.

This invention relates to a fabric which is more particularly intended as a non-squeak strip between the cowls and radiators and the hoods of automobiles although the same 5 may also be used to advantage in other installations where similar conditions exist.

In the strips of fabric as heretofore constructed it has been customary to employ woven cotton in the fabric of the body and 10 to embody a cord of twisted paper in a tube on one edge of the body for the purpose of forming a rib or raised edge thereon which supports the hood on the cowl and the radiator and which will not flatten readily and 15 therefore hold the hood away from the rivets or other means which fasten the body of the anti-squeak strip to the cowl and radiator and thus prevents noise.

It has been found, however, that when the 20 weaving of the cotton body and the formation of a tube on one edge thereof around a paper cord has been completed and the strip thus formed is released that the same tends to curve or curl. The reason for this is that 25 the cotton is stretched but the paper cord is not stretched during operations of weaving the same with the result that when the fabric containing the paper cord in one of its longitudinal edges is taken from the 30 loom, the cotton draws back or shrinks so as to assume its former normal length, but the paper cord remains practically of the same length inasmuch as the same does not stretch while under tension during the weaving operation in the loom.

The object of this invention is to so construct a fabric strip of this character so that the same will not curl or curve when taken 40 from the loom and thereby facilitate mounting the same on the cowl and the radiator as an anti-squeak strip for the hood and also present a neater and more finished appearance.

With this end in view this invention consists generally in weaving or braiding into the non-raised, non-ribbed or non-beaded edge of the strip of woven fabric one or more strands of non-stretchable fibres such as jute, linen, rayon or paper, whereby this edge is 45 held straight and prevented from curling, bending or curving when the material is

taken from the loom and the objectionable condition referred to is avoided.

In the accompanying drawings:

Figure 1 is a fragmentary perspective view showing an anti-squeak strip embodying this invention interposed between the casing of a radiator and the hood of an automobile.

Figure 2 is a plan view of a portion of this strip.

Figure 3 is an edge view of the same looking at the non-raised or non-beaded edge thereof.

Figure 4 is a transverse section of the same, on an enlarged scale, taken on line 4—4, Figure 2.

In the following description the same reference characters indicate like parts in the several figures of the drawings.

The numeral 10 represents the movable hood or covering of an automobile engine which is adapted to rest at its front and rear edges on supports provided on the radiator and cowl of the automobile. In Figure 1 75 this support is represented in the form of a flange 12 projecting rearwardly from the casing 13 of the radiator and it is to be understood that a similar flange is provided on the cowl for supporting the hood.

Upon this support is mounted a fabric 80 having the general form of a strip which is interposed between this support and the hood so that when the latter rests on the support through the medium of this strip no 85 squeaking noise will be caused during the operation of the car inasmuch as there is no metallic contact between the hood and this support.

This strip comprises a body of fabric 90 which is woven of strands of stretchable material, such as cotton, to form a comparatively flat web 11 and a longitudinal tube 14 at one of the longitudinal edges thereof. While weaving this body a core or gutting 95 15 of non-stretchable and non-compressible material is fed to the body during the formation of the same in the loom, so that the tube is woven around the core at the same time that the web of the strip is woven. 100 This core or gutting preferably consists of a cord of twisted paper which is practically

non-stretchable and also substantially non-compressible and, therefore, produces on the tubular edge of the body on which the same is located a raised bead, rib or edge 16 so that when the web of this strip is secured to the supporting flange 12 by means of rivets 17 or other fastening the hood 10 will engage with this raised edge or bead and be prevented from contacting with these rivets 10 and the flange and thereby avoiding squeaking noises.

In the non-raised edge of the web one or more strands 18 of non-stretchable material are woven into the web during the operation 15 of weaving the same in the loom, two of such strands being shown in the drawings, inasmuch as the same have been found satisfactory in practice but a lesser or greater number may be employed as best suits the 20 particular requirements. Various materials may be used for the non-stretching strands in the non-beaded edge of the web. For example, jute, linen, rayon and paper, but it is preferable to use jute on account of its 25 low cost, strength and serviceability.

When the strip having the cotton body, the non-stretching paper core in one edge thereof and the non-stretching strands of jute in the other edge thereof are assembled 30 in the loom the cotton while under tension will stretch but the paper cord and the jute strands will not stretch. As a result the finished strip when taken out of the loom will not bend, curl or buckle inasmuch as 35 both edges of the strip contain non-stretchable material and, therefore, will not be influenced by the tendency of the cotton body to contract when the tension on the same while in the loom is relaxed.

40 The strip can, therefore, be applied easily, conveniently and regularly on the support

of an automobile for use as an anti-squeak strip between the hood and the radiator and cowl and effectively operate to prevent metallic contact between these members and 45 thereby avoid objectionable noise.

Moreover, this anti-squeak strip can be produced expeditiously and without any added cost inasmuch as the operation of supplying the jute or the like for the non-raised edge of the web is virtually no greater than if the web were made of cotton or the like.

I claim as my invention:

1. A fabric for use as an anti-squeak 55 strip comprising a fabric body woven of stretchable strands and having a flat web and a tube at one edge thereof, a core of non-stretchable material arranged within said tube to form a longitudinal raised bead 60 on the respective edge of the body and a non-stretchable material woven into the opposite non-raised edge of the web.

2. A fabric for use as an anti-squeak strip comprising a fabric body woven of 65 cotton and having a flat web and a longitudinal tube at one edge thereof, a core of paper cord arranged within said tube and forming a raised edge thereon, and a strand of non-stretchable material woven into the 70 non-raised edge of said web.

3. A fabric for use as an anti-squeak strip comprising a fabric body woven of cotton and having a flat web and a longitudinal tube at one edge thereof, a core of paper cord arranged within said tube and forming a raised edge thereon and a strand of jute woven into the non-raised edge of 75 said web.

In testimony whereof I hereby affix my 80 signature.

WILLIAM C. MEYER.
